BOBBIN HOLDER

Arthur F. Anderson, Auburn, Mass., and Robert G. Carle, Woonsocket, R. I., assignors to Johnson & Bassett, Inc., Worcester, Mass., a corporation of Massachusetts

Application June 3, 1940, Serial No. 338,532

5 Claims. (Cl. 242—46.8)

This invention relates to spindles used in mules or other spinning and twisting machines, and relates more particularly to improved means for centering and driving a bobbin mounted thereon.

5 It is the general object of our invention to provide an improved construction in a bobbin holder, by which a bobbin will be positively centered as well as frictionally engaged and driven.

More specifically, we provide rigid bobbin-centering members alternately disposed with respect to the usual yielding devices which drive the bobbin by frictional engagement.

Our invention further relates to arrangements and combinations of parts which will be herein-after described and more particularly pointed out in the appended claims.

Preferred forms of our invention are shown in the drawing, in which

Fig. 1 is a side elevation of a portion of a mule spindle embodying one form of our invention;

Fig. 2 is a sectional plan view, taken along the line 2—2 in Fig. 1;

Fig. 3 is an enlarged plan view similar to Fig. 2 but with certain parts omitted for the sake of clearness;

Figs. 4 and 5 are partial sectional elevations, taken along the lines 4—4 and 5—5 in Fig. 3 respectively;

Fig. 6 is a front elevation of a bobbin-engaging and driving member; and

Figs. 7 and 8 are partial sectional elevations similar to Figs. 4 and 5 but showing a modified construction.

Referring to the drawing, we have shown a portion of a mule spindle having a blade 10 and whirl 11 and adapted to receive a bobbin B which preferably has double-beveled base flanges 12, all of these parts being of the usual construction.

Our improved bobbin holder, as shown in Figs. 40 1 to 6, comprises a hub 20 adapted to be forced with a press fit on the blade 10. The hub 20 has a flange 21 to receive a cup 22 and a plate or disc 23, which parts are held firmly on the hub 20 by an outwardly displaced or swedged 45 portion 24.

The cup 22 has a plurality of equally spaced and inwardly offset upstanding centering members or ears 25 formed on its upper edge and positioned to engage the periphery of the bobbin base 12 and to thereby positively center the bobbin B on the spindle. The plate or disc 23 fits within the rim of the cup 22 and is provided with notches 30 to clear the offset members 25 and with notches 31 which are also equally spaced 55 apart and which alternate with the notches 30.

Bobbin-engaging and driving devices 32 are loosely mounted in the notches 31, which devices are cut away at the edges as indicated at 33 and are held from upward displacement by lower lugs 34. At their upper edges, the driving devices 32 are flanged outward as indicated at 35 to guide a new bobbin to its seat and also to retain an encircling spring 36 by which the devices 32 are forced yieldingly inward against a bobbin base 12.

5 The base 12 fits with slight clearance between the rigid centering members 25, which thus position the bobbin concentric with the blade 10. At the same time, the driving devices 32 frictionally engage the periphery of the flange 12 and supply frictional force to rotate the bobbin.

10 Under present commercial practice, the bobbins B are of substantial length and when filled with yarn are much heavier than the bobbins previously used. There is accordingly an increased chance for an unbalanced weight to throw a bobbin out of center with its spindle, which tendency is effectively offset by our rigid upstanding centering members. The parts 20, 22 and 23 collectively form a support which vertically positions the bobbin B.

15 In Figs. 7 and 8, we have shown a modified construction in which the upstanding centering members 40 are formed on the disc 41 rather than on the upper edge of the cup 42. The same driving members 32 and spring 36 are used as in the previous form and the operation and advantages of the two forms of our invention are substantially identical.

Having thus described our invention and the advantages thereof, we do not wish to be limited to the details herein disclosed, otherwise than as set forth in the claims, but what we claim is:

20 1. In a spindle, a bobbin holder comprising a bobbin support fixed on said spindle, a plurality of movably-mounted bobbin-driving devices rotatable with said support, and bobbin-centering members interposed between said bobbin-driving devices and concentrically disposed relative to said spindle.

2. In a spindle, a bobbin holder comprising a bobbin support fixed on said spindle, a plurality of equally-spaced movably-mounted bobbin-driving devices mounted on and rotatable with said support, and equally-spaced upstanding 50 bobbin-centering members interposed between said bobbin-driving devices and concentrically disposed relative to said spindle.

3. In a spindle, a bobbin holder comprising a hub fixed to said spindle, a cup and a notched 55

disc mounted in fixed spaced relation on said hub, bobbin-centering members fixed on one of said latter parts, bobbin-driving devices mounted in peripheral notches in said disc and having portions retained below said disc, and means to yieldingly press said devices against the base of said bobbin.

4. In a spindle, a bobbin holder comprising a hub fixed to said spindle, a cup and a notched disc mounted in fixed spaced relation on said hub, bobbin-centering members fixed on the edge of said cup, bobbin-driving devices mounted in peripheral notches in said disc and having portions retained below said disc, and means to

yieldingly press said devices against the base of said bobbin.

5. In a spindle, a bobbin holder comprising a hub fixed to said spindle, a cup and a notched disc mounted in fixed spaced relation on said hub, bobbin-centering members fixed on the edge of said disc, bobbin-driving devices mounted in peripheral notches in said disc and having portions retained below said disc, and means to yieldingly press said devices against the base of said bobbin.
